PARIS R. FORMAN, OF CHICAGO, ILLINOIS, ASSIGNOR TO NATIONAL PNEUMATIC COMPANY, OF CHICAGO, ILLINOIS, A CORPORATION OF WEST VIRGINIA.

PNEUMATIC MOTOR MECHANISM.

1,184,172.

Specification of Letters Patent.

Patented May 23, 1916.

Application filed March 8, 1912. Serial No. 682,526.

To all whom it may concern:

Be it known that I, PARIS R. FORMAN, a citizen of the United States, residing at Chicago, county of Cook, and State of Illinois, have made a certain new and useful Invention in Pneumatic Motor Mechanism, of which the following is a specification.

This invention relates to pneumatic motor mechanism.

10 The object of the invention is to provide a pneumatic motor mechanism which is simple in construction and efficient in operation.

Other objects of the invention will appear 15 more fully hereinafter.

The invention consists substantially in the construction, combination, location and relative arrangement of parts, all as will be more fully hereinafter set forth as shown in 20 the accompanying drawing and finally pointed out in the appended claims.

Referring to the accompanying drawing, and to the various views and reference signs appearing thereon,—Figure 1 is a view in 25 longitudinal central section taken through the ports 2 and 4, Fig. 2, of a pneumatic motor mechanism embodying the principles of my invention. Fig. 2 is a view in end elevation of the valve seat employed in connection with my invention. Fig. 3 is a view 30 in section on the line 3, 3, Fig. 1, looking in the direction of the arrows and showing the relation of the valve ports with reference to the seat ports with which the valve ports 35 coöperate. Fig. 4 is a view similar to Fig. 3, taken on the same section line, showing a displaced position of the valve and its ports as will be more fully hereinafter explained. Figs. 5, 6, 7 and 8 are diagrammatic views illustrating modified forms of 40 valves, adapted for use in connection with my invention.

In carrying out my invention I employ two cylinders 5, 6, of relatively different 45 areas, the larger cylinder being designated by reference sign 5, and the smaller cylinder by reference sign 6. In the particular form shown, to which however, my invention, as defined in the claims, is not to be limited 50 or restricted, the cylinders 5, 6, are arranged in axial alinement with each other, and are open-ended at the proximate ends thereof. Operating in these cylinders are pistons which, in the case of the larger cylinder 5,

comprises the heads 7, 8, and in the case of 55 the smaller cylinder 6, comprises the heads 9, 10. Where the cylinders 5, 6, are arranged in line with each other a common piston rod 11, is employed which extends through the open proximate ends of the cylinders and carries the piston heads 7, 8, 9, 10. The piston heads 7, 8, are suitably spaced apart upon the rod 11, by a spacing sleeve 14. Similarly a spacing sleeve 15, interposed between the piston heads 9, 10, 60 serves to separate the same. Also mounted upon and connected to the piston rod 11, is a cross-head 16. This cross head may be separated from the piston head 8, by means of a spacing sleeve 17 and also from the piston head 9, by a similar spacing sleeve 18. The clamp nuts at the ends of the piston rod serve to clamp these several parts together on said rod. The closed end of the smaller cylinder 6, 65 is in communication with a supply tank for compressed air, or other operating medium through a pipe connection 19, which communicates with the interior of the cylinder 6, at two points, one point being indicated at 20, intermediate the ends of the cylinder, 70 this being a port of large area, and at the point 21, closely adjacent the closed end of said cylinder through a port of small area. These ports 20, 21, are in constant communication with the pressure supply source or 75 tank and no control or valve mechanism therefor is necessary.

It is necessary to control the supply and exhaust of the operating medium to and from the closed end of cylinder 5. This control, is effected by means of a valve mechanism comprising a cap 25, within which is mounted the valve 26. The valve 26 is provided with suitable port openings, indicated at 1^a, 2^a, 3^a, 4^a, (see Figs. 3 and 4). The valve 26, coöperates with a valve seat or surface 27, (see Fig. 2) being the outer surface of the closed head 28, of the cylinder 5. In this valve surface or head 28 are formed ports, passages or openings 1, 2, 3, 4, with 80 which respectively coöperate the valve ports 1^a, 2^a, 3^a, 4^a. The valve is provided with ducts or passages 29 and 30, which respectively connect the ports 1^a, 2^a, or the ports 3^a, 4^a, as indicated in dotted lines in Figs. 3 and 4. The valve 26 is held to its seat, against the surface 27, in any suitable or 85 convenient manner, preferably by means of

a spring 31, arranged within a cup 32 arranged within the cap 25, (see Fig. 1). The cup 32 is provided with a rod 33, by which said cup may be axially rotated. A 5 pin or other form of projection 34, carried by the cup 32, engaging with lugs 35, on the valve, serves to rotate said valve when said cup, or its actuating rod 33, is rotated. The port 4, in the valve seat 27, communicates 10 with the interior of the closed end of the cylinder 5, as shown in Fig. 1. The port marked 3, in Fig. 2, communicates with the source of pressure supply or tank, or other convenient source, through a pipe connection 15 36. The port 1, communicates through a suitable connection to exhaust. Through the head 28, is formed a port opening or passage 2, shown also in Fig. 2, and said port opening communicates with a passage 20 22, with which communicates a port 36, of large area, opening into the cylinder at a point intermediate its ends, and also a port 23, of small area which opens into the cylinder 5, adjacent to the closed end thereof. 25 The dotted lines shown in Fig. 2 as connecting certain ports, indicate the two positions of the valve 26.

The cylinders 5, 6, may be supported in assembled relation in any suitable or convenient manner. A simple and efficient support for said cylinders is shown wherein said cylinders are swaged into rings 37, 38, forming portions of a supporting base 39. Similarly, the passage or duct 22 may be formed 30 in a casting 40, which is also swaged upon the cylinder 5, by means of rings or bands 41, encircling said cylinder. The cross head 16 may be connected in any suitable or convenient manner with the part to be moved or 35 operated by the motor.

A pneumatic motor mechanism embodying the principles of my invention is particularly well adapted for the operation of doors. In this particular use of motor 40 mechanism of my invention, I employ a pivoted lever 42, connected to the cross-head 16, and having rods 43, 44 connected to said lever 42, on opposite sides of its pivot point 45, said rods being respectively connected to 45 the door sections or panels or other parts to be operated. Of course, other suitable forms of connecting mechanism to the part to be operated may be employed and will readily suggest themselves in the details thereof to 50 persons skilled in the art.

The operation of a motor mechanism embodying the principles of my invention is very simple and will be readily understood. The pressure medium is constantly supplied 55 to the closed end of the smaller cylinder 6. In the position of the parts as indicated in Fig. 1, the piston heads are at the left hand limit of their movement or stroke. In this position the door or other part to be moved 60 is in one of the limits of its movement. In

this position pressure medium is acting upon the smaller pistons 9, 10, from the pressure supply source or tank, and serves to retain the door or other part in its corresponding limit of movement. Now if it is desired to 70 operate the door, or other part to be moved, in the opposite direction, the valve 26, is actuated so as to bring the ports 1^a, and 2^a, respectively, into communication with the valve seat ports 3, 4. This operation will 75 open the source of pressure supply from the tank to the cylinder 5 through the connection 36, port 3, of the valve seat, port 1^a of the valve duct or passage 29, port 2^a of the valve and port 4, into the closed end of the 80 larger cylinder 5. The door or other part to be moved will thereupon take up its movement rapidly, the excess of area of the pistons 7, 8, over that of the pistons 9, 10, causing the pistons to be shifted or moved toward the right. During this movement the pressure contained in the closed end of cylinder 6, is forced back into the pressure tank, at first through the large area port opening 20, as well as through the smaller area of 85 opening 21, thereby insuring a rapid initial movement of the door or other part to be moved. As the piston heads 9, 10, continue to travel toward the right they eventually 90 cover the large exhaust port 20, of cylinder 6, and thereafter the exhaust from the closed end of said cylinder is effected only through the port of restricted area 21. Consequently 95 the movement of the part to be moved is cushioned as it approaches the final limit of such movement.

It will also be seen that the power applied to the pistons 7, 8, of the larger cylinder operates against the constant live pressure of the pressure medium which is constantly applied in the closed end of cylinder 6 and which constantly tends to return or restore the pistons toward the left when the closed end of the larger cylinder 5 is open to exhaust. This is a beneficial arrangement as it secures a smooth easy working of the part to be moved. After operating the apparatus in the manner above described, if it is desired to shift or move the door or other part again toward the left, the valve 26, is actuated so as to bring the ports 4^a, 3^a and the duct 30, respectively into communication with the valve seat ports 2 and 1. This movement opens the closed end of the larger cylinder 5, to exhaust, while at 100 the same time cutting off the tank pressure by closing the port 3, as well as the port 4. By bringing the valve seat ports 2 and 1 into communication with each other the closed end of the larger cylinder 5, is opened to full and free exhaust, at first through the large exhaust port opening 36, and channel 22, thereby insuring a rapid initial movement toward closing position, for instance, of the door or other part to be moved, but 105 110 115 120 125 130

when the piston heads 7, 8, progress toward the left a distance sufficient to cover the large exhaust port 22, the exhaust thereafter from the closed end of cylinder 5, is through the 5 smaller port opening 23, and consequently the final closing movement or final movement of the part to be moved, is effected against the cushioning action afforded by the restricted exhaust of the medium contained 10 in the closed end of the cylinder through the port 23, of the small area.

It will be seen that only two positions of the valve 26 are necessary, one where the ports 3^a, 4^a, are brought into communication 15 with each other, or with the ports 1, and 2, of the valve seat and the other position being that of the valve which brings the port 1^a, 2^a, thereof into communication with the ports 3, and 4, of the valve seat.

20 It will be seen that the valve, as well as the seat with which it coöperates, is provided with four port openings in the face thereof, the ports in the valve face being connected in pairs by ducts or channels 29, 25 30. In the arrangement shown in Figs. 5 and 6, the valve is provided with only two port openings, these being connected by a duct or channel 40, while in Figs. 7 and 8, the valve is shown as having three port 30 openings all connected by ducts or channels 41, 42. My invention, therefore, in its broadest scope, as defined in the claims, is not to be limited in respect to the particular structure of valve employed.

35 In the arrangement of Fig. 5 the valve is in position for the seat ports 1 and 2 to be brought into communication with each other. This cuts off the pressure supply to the large cylinder and opens the same to 40 exhaust, first through the large area of passage 22, and finally through the small area of duct 23. In Fig. 6, the valve is in position to open communication between seat ports 3 and 4. This cuts off the exhaust 45 connections and supplies pressure to the cylinder.

It may sometimes be desired to omit the 50 small exhaust passage 23, from the cylinder, and to employ a passage of reduced area in the valve itself to accomplish the same function. This is the arrangement shown in Figs. 7 and 8. The duct or passage 42 is formed in the valve and communicates with the larger duct or passage 41, therein so as to connect up all the valve parts. In Fig. 7 the valve is shown in position for large area passage 41 to connect the ports 1 and 2, to exhaust the cylinder, the smaller passage 42, opening port 4 to exhaust through passage 41. Now, since in this case, the exhaust passage 23 is omitted, as soon as the piston 7 closes the passage 36, the exhaust thereafter will continue only through the port 4 the restricted passage 42, 60 passage 41, and port 1. When the valve

is moved into the position indicated in Fig. 8 then the pressure is freely admitted into the end of the cylinder through port 3, passage 41, and port 4, and would also pass to some extent through the small area passage 42 70 and port 2 and thence into the space between pistons 7 and 8, there equalizing against the piston surfaces and hence not causing any trouble. It is obvious that the valve may be operated in any suitable or 75 convenient manner and from any suitable or convenient point.

A pneumatic motor mechanism embodying the principles of construction above described and indicated, is not only simple 80 and efficient, but is exceedingly economical to manufacture, and may be readily and easily assembled and installed. The parts are few and easily manufactured, thereby very greatly reducing the cost and the expense of manufacture of motors of this nature.

Having now set forth the object and nature of my invention, and a construction embodying the principles thereof, what I 90 claim as new and useful, and of my own invention, and desire to secure by Letters Patent of the United States, is:—

1. In a pneumatic motor mechanism, differential cylinders, each having a closed and an open end, a pair of spaced pistons respectively operating in each of said cylinders, each pair of said pistons being connected together through the open ends of the cylinders and to the part to be moved, the closed end of one of said cylinders being constantly in communication with a source of supply of operating medium through a port of large area, communicating with the cylinder at a point intermediate the ends of said cylinder, and also through a port of small area at the closed end thereof, and means for controlling the supply and exhaust of operating medium to and from the closed end of the other cylinder.

2. In a pneumatic motor mechanism, differential cylinders, each having a closed and an open end, a pair of spaced apart pistons respectively operating in each of said cylinders, said pistons being connected to the parts to be moved, the closed end of the smaller of said cylinders being constantly in communication with a source of supply of operating medium through two ports, one of said ports being of large area, and the other of small area, the port of large area being located intermediate the ends of said cylinders and the port of small area being located adjacent the closed end of said cylinder and means for controlling the supply and exhaust of operating medium to and from the closed end of the other or larger cylinder.

3. In a pneumatic motor mechanism, differential cylinders independent of and arranged

- in alinement with each other closed at their remote, and open at their proximate ends, a pair of spaced apart pistons respectively operating in each of said independent cylinders, 5 a piston rod common to said pistons, connections between said piston rod and the part to be moved, one of said cylinders being constantly in communication through a plurality of ports at relatively different distances from the closed end thereof with a source of supply of operating medium, and means for controlling the supply and exhaust of operating medium to and from the closed end of the other cylinder.
- 10 4. In a pneumatic motor mechanism, differential cylinders independent of and arranged in alinement with each other, a pair of spaced apart pistons respectively operating in each of said independent cylinders, 15 a piston rod common to said pistons, a cross head connected to said piston rod and connected to the part to be moved, the cylinder of smaller area being constantly in communication through a plurality of ports at 20 relatively different distances from the closed end thereof with a source of supply, and means for controlling the supply and exhaust of operating medium to and from the other cylinder.
- 25 5. In a pneumatic motor mechanism, differential cylinders arranged in alinement with each other, closed at their remote and open at their proximate ends, a pair of spaced apart pistons respectively operating 30 in each of said cylinders, a piston rod common to said cylinders, a cross head connected to said piston rod and adapted to be connected to the part to be moved, the smaller cylinder being constantly in communication 35 at its closed end with a source of supply of operating medium through two ports, one of said ports being of large area, and located at a point intermediate the ends of said cylinder, and the other of said ports being of 40 restricted area, and communicating with the cylinder at a point adjacent its closed end, and means for controlling the supply and exhaust of operating medium to and from the closed end of the larger cylinder.
- 45 6. In a pneumatic motor mechanism, differential cylinders, each having a closed and an open end, a pair of spaced apart pistons respectively operating in each of said cylinders, said pistons being connected to the part 50 to be moved, one of said cylinders being constantly in communication at its closed end with a source of supply of operating medium, a valve for controlling the supply and exhaust of operating medium to and 55 from the closed end of the other cylinder and having pressure supply and exhaust port openings, and exhaust openings respectively of large and small area communicating with the interior of said last mentioned cylinder, and controlled by said valve,
- 60 the exhaust port of large area communicating with the cylinder intermediate the ends of said cylinder.
- 65 7. In a pneumatic motor mechanism, differential cylinders each having a closed and an open end, and arranged in alinement with each other, a pair of spaced apart pistons respectively operating in each of said cylinders, a piston rod common to said pistons, a cross head connected to said piston rod and adapted to be connected to the part to be moved, one of said cylinders being constantly in communication at its closed end with a source of supply of operating medium, a valve for controlling the supply and exhaust of operating medium to and from the closed end of the other cylinder and having pressure supply and exhaust port openings, and exhaust openings respectively of large and small area communicating with the interior of said other cylinder, and controlled by said valve, the exhaust port of larger area communicating with the cylinder intermediate the ends of said cylinder and the exhaust port of small area located at the closed end of said cylinder.
- 70 8. In a pneumatic motor mechanism, differential cylinders, connected pistons respectively operating in said cylinders, said pistons being connected to the part to be moved, one of said cylinders being constantly in communication with a source of supply of operating medium, a closed head for the other of said cylinders, said closed head having port openings therethrough, and the outer surface thereof forming a valve seat, a valve fitted to said seat and having ports and passages, for controlling the supply and exhaust of operating medium to and from said cylinder, a spring for retaining said valve to its seat, an inclosing cap for said valve, and means for operating said valve.
- 75 9. In a pneumatic motor mechanism, differential cylinders, connected pistons respectively operating in said cylinders, said pistons being connected to the part to be moved, one of said cylinders being constantly in communication with a source of supply of operating medium, means for controlling the supply and exhaust of operating medium to the other cylinder, a supporting base for said cylinders, and rings swaged upon said cylinders to form a supporting connection therefor with said base.
- 80 10. In a pneumatic motor mechanism, differential cylinders each having a closed and an open end, a pair of spaced apart and connected pistons respectively operating in each of said cylinders, said pistons being connected to the part to be moved, each of said cylinders having a port opening of large area intermediate its ends and a port of small area adjacent its closed end, one of said cylinders being in constant communication through both its large and small port
- 85 90 95 100 105 110 115 120 125 130

openings with a source of pressure supply, and means for controlling the supply and exhaust of operating medium to and from the other of said cylinders.

- 5 11. In a pneumatic motor mechanism, differential cylinders, each having a closed and an open end, a pair of spaced apart and connected pistons respectively operating in each of said cylinders, said pistons being connected to the part to be moved, one of said cylinders being constantly in communication with a source of supply of operating medium through a port opening of large area, located intermediate its ends and also 10 through a port of restricted area adjacent its closed end, a pressure supply port for the closed end of the other of said cylinders, exhaust port openings also communicating with said other cylinder, one of said port openings being of large area and located intermediate the ends of said cylinder, and the other of said port openings being of restricted area and located adjacent the closed end of said cylinder, and a valve mechanism for 15 controlling said port openings.
12. In a pneumatic motor mechanism, differential cylinders each having an open and a closed end, and arranged in alinement with each other, a pair of spaced apart pistons respectively operating in said cylinders, a piston rod common to said cylinders and operating through the open proximate ends of said cylinders, a cross head connected to said piston rod and adapted to be connected 20 to the part to be moved, one of said cylinders being constantly in communication with a source of supply of operating medium through ports, one of which is of large area and located intermediate the ends of said cylinder and the other being of restricted area and located adjacent the closed end of said cylinder, a supply port opening for the closed end of the other of said cylinders, and exhaust ports communicating with said 25 other cylinder, one of said exhaust ports being of large area, and communicating with said cylinder at a point intermediate its ends and the other of said exhaust ports being of restricted area and communicating 30 with said cylinder adjacent its closed end,

and a valve mechanism for controlling said port openings.

13. In a pneumatic motor mechanism, two cylinders arranged in alinement with each other, pistons respectively operating in said cylinders, said pistons having a common connecting rod operating through the open proximate ends of said cylinders, a cross head connected to said piston rod and adapted to be connected to the part to be moved, the cylinder of smaller size having port openings in constant communication with a source of pressure supply, one of said port openings being of large area and located intermediate the ends of said cylinder, and the other of said port openings being of restricted area and located adjacent the closed end of said cylinder, the closed end of said larger cylinder having a pressure supply port opening and exhaust port openings, one of the latter being of larger area and located intermediate the ends of said cylinder, and the other of said exhaust openings being of restricted area, and located adjacent the closed end of said cylinder, and a valve for controlling said port openings.

14. In a pneumatic motor mechanism, differential cylinders, connected pistons respectively operating in said cylinders, said pistons being connected to the part to be moved, one of said cylinders being constantly in communication with a source of supply of operating medium, means for controlling the supply and exhaust of operating medium to the other cylinder, a supporting base for said cylinders and rings swaged upon one of said cylinders and having an exhaust passage through the body thereof, and communicating with said cylinder at a point intermediate its ends.

In testimony whereof I have hereunto set my hand in the presence of the subscribing witnesses, on this 20th day of February A. D., 1912.
